UNITED STATES PATENT OFFICE.

THEODOR MISTELSKI, OF ALLEGHENY, PENNSYLVANIA.

SAND-MOLDING MACHINE.

SPECIFICATION forming part of Letters Patent No. 430,666, dated June 24, 1890.

Application filed March 12, 1890. Serial No. 343,602. (No model.)

To all whom it may concern:

Be it known that I, THEODOR MISTELSKI, a citizen of the United States, residing at Allegheny, in the county of Allegheny and State of Pennsylvania, have invented certain new and useful Improvements in Sand-Molding Machines; and I do hereby declare the following to be a full, clear, and exact description of the invention, such as will enable others skilled in the art to which it pertains to make and use the same, reference being had to the accompanying drawings, which form a part of this specification.

My invention relates to machines for molding molds for casting, and more especially to that class of such machines in which the flask is brought under a platen which compresses and packs the sand around the pattern, the flask being then removed from under the platen and the pattern withdrawn.

My invention consists, first, in the combination, with a stationary support for the platen, of a reciprocating carriage, upon which are mounted the tables on which the flasks are placed; second, in means for moving the carriage back and forth under the platen and for stopping it automatically or otherwise at any desired point in its travel; third, in a table for supporting the flask, made adjustable to suit flasks of different sizes; fourth, in a movable banking-frame adapted to be applied to a flask at either side of the platen and to move with the flask when the carriage is operated, and, fifth, in certain details of construction and arrangement that will be hereinafter set forth, and particularly pointed out in the claims.

In the drawings, Figure 1 is a side elevation of my improved machine. Fig. 2 is an end view, certain parts being shown in cross-section. Fig. 3 is a plan of the banking-frame and its guides. Fig. 4 is a perspective view of the bed. Fig. 5 is a longitudinal section of one of the tables. Fig. 6 is a plan view of the mechanism for enlarging or contracting the tables. Fig. 7 is a longitudinal section of the carriage; and Fig. 8 is a cross-section thereof, showing the same mechanism.

The same letters and numerals of reference are used in all figures.

The bed A is a solid rectangular casting,

resembling an open box. It may be stiffened by transverse partitions a. Lugs a' are cast integral with the bed, projecting from each side and at oppositely-disposed points, preferably in line with the partitions a. In a hole in each lug is stepped a standard B, which is preferably a stout round rod threaded at its lower end, and firmly fastened in the lug by the nuts b. A head or collar integral with the rod may take the place of the lower or upper nut, respectively, or any other convenient mode of fastening the standard may be adopted. The standards are preferably four in number, and rise parallel with each other to a suitable height above the bed. Their upper ends pass through eyes in a plate C, which can be adjusted vertically on the standards, preferably by means of nuts c above and below the eyes, the upper portion of the standards being screw-threaded to receive said nuts. The plate supports a vertical cylinder C', preferably cast in one piece with it. A head c' is secured to the upper end of the cylinder, and within it is fitted a piston D, whose piston-rod D' passes downward through a stuffing-box c' beneath the plate C. To the end of the piston-rod is fastened a movable cross-head E, consisting of a plate having perforated lugs e, that slide on the standards B and guide it in its vertical movements. A box F is secured on the under side of the plate by means of bolts passing through a flange f. The sides of the box may slope inward slightly, as shown, and its bottom is composed of a sheet of rubber or other suitable flexible material F', which is clamped to the edge of the box by means of a frame f' and bolts or screws f'.

A pipe G, passing through the cross-head E to the interior of the box F, enables the box to be filled with water or other liquid, after which a valve in the pipe can be closed to confine the liquid and cause it to form an incompressible but mobile backing for the flexible sheet F'. When this platen is forced down upon the sand in a flask, the sand is packed tightly around the pattern with an even uniform pressure, due to the fact that the sheet F' will yield where the sand is harder on the pattern nearer the surface, and will bulge out and follow up the sand in those

places where it is softer or deeper, thereby packing it to the same density at all points.

In order to raise and lower the platen and cause it to exert a pressure upon the sand, a pipe H conveys compressed air, steam, or other fluid under pressure to the cylinder C' through the branches h h', one delivering the fluid-pressure above the piston D and the other underneath it. The fluid is directed into the desired branch pipe by means a four-way cock H', located at the junction of the branches with the main pipe. By turning the cock to one position the piston and platen will be raised. On turning the cock to another position the piston will be depressed, forcing the platen down upon the mold. The construction and operation of the four-way cock are so well known that they need not be described here in detail. A gage I indicates the pressure in the cylinder above the piston.

Turning now to the devices by which the flasks are brought under the platen and removed therefrom, it may be said that this comprises a reciprocating carriage, on which are erected tables for supporting the flasks, the carriage being moved by a piston in a long cylinder, and the tables being adjustable in length. Inside of each table is a vertically-moving cross-head, to which the pattern is attached.

In the drawings, the carriage K appears as a rectangular open frame or box having projecting flanges k along the lower edges of its sides, which are received in grooves a³, formed along the upper edges of the sides of the bed A, and serving as ways in which the carriage slides. Within the bed is a cylinder A' of suitable length, disposed longitudinally of the bed, and preferably cast integral therewith. A piston in the cylinder is provided with a piston-rod L, which extends through a slot a³ in the end of the bed, and is secured to an arm k', depending from one end of the carriage K. A pipe M conveys steam, compressed air, or the like to a four-way cock M', which directs it into one or the other of two branches m m', leading, respectively, to the front and rear ends of the cylinder A', the exhaust-fluid escaping through the branch m². The spindle of the valve M' extends out through the bed A, and is provided with an upright rock-arm M² and a horizontal one M³. By manipulating the cock M' the carriage K can be reciprocated to bring either of the tables N under the platen.

Each table is composed of two end portions n n, separated by an intermediate removable portion n'. The end portions consist of boxes having two sides, one end, and a bottom, the latter extending beyond the sides to form flanges n², that fit into the grooves k², formed along the inside of the carriage K at its upper edges. Depending from the bottom of each portion n n is a lug n³, in which is a screw-threaded hole, one having a right-hand and the other a left-hand thread. A shaft O extends longitudinally through the carriage,

being suitably journaled in bearings in the ends of the carriage and in its transverse stiffening-webs k³. The shaft is reduced in diameter at one end, as shown, from a point about midway of the table N, and is screw-threaded on both the larger and smaller portions, the threads being alternately right hand and left hand, as shown. This screw-shaft engages the lugs n³ on the several end portions of the tables, the reduced diameter of the end of the shaft permitting the inner lug n³ to slip freely over it when the parts are assembled until it reaches its own larger thread. The shaft may be provided at one end with a squared portion, as shown in Fig. 5, for the application of a wrench or crank-handle to rotate it when the tables are to be altered in size. Inasmuch, however, as this might at times require considerable power I prefer the construction illustrated in Figs. 6, 7, and 8, in which is shown an arrangement of gearing for rotating the shaft.

At some convenient point on the shaft, preferably between the webs k³, a worm-gear o is secured to it, which meshes with a worm o' on a transverse shaft O', suitably journaled in the sides of the carriage. One end of the shaft O' protrudes sufficiently to allow a removable winch or crank-handle O² to be applied to it when desired. Upon turning the worm-shaft O' the screw-shaft O will be rotated and the end portions of the tables will be separated or caused to approach each other simultaneously, according to the direction in which the screw is rotated. When the parts have been properly adjusted, they can be clamped in position by means of the set-screws k⁴ impinging upon the flanges n². The intermediate removable portions n' have no bottoms nor any flange to enter the grooves k². They are made in sets of different widths, corresponding with the different sizes to be given to the tables. They are fastened to the end portions by bolts that pass through registering-lugs formed on the meeting edges of the end portions and removable portions, as clearly shown in Figs. 1 and 2. The top of the table is a plate N', and may be provided with a depending flange n⁴ to fit over the outside of the portions n n'. Plates of various sizes are necessary, and in each is cut an aperture n⁵, corresponding with the shape of the pattern, since the table-top operates as a stripping-plate, through which the pattern is projected and withdrawn.

The pattern is fastened on a platform P, a set of which is provided of different sizes corresponding to the sizes that can be given to the tables. This platform P is removably secured to the upper ends of posts p, which rise from the ends of a cross-head P', arranged to slide in vertical guides Q on the inside of the carriage K. The posts p pass up between the bottoms of the two end portions n n of the table alongside of the removable portions n'. The cross-head may be suitably cut away to avoid striking the screw O when raised. The

travel of the cross-head must be enough to withdraw the pattern Z from the mold.

To operate the cross-head, it is provided at each end with a wrist-pin p' , which projects 5 through a vertical slot k^5 in the side of the carriage K. Each pin is connected by a link r with an arm 1 of a T-shaped rocker R, keyed on the end of a rock-shaft R', which is mounted in bearings in the sides of the carriage across 10 which it extends. A second rock-shaft S is arranged transversely of the carriage near the rock-shaft R, and is provided with a lever-handle s, and a rock-arm s', which is connected by the link s^2 with another arm 2 of the rocker 15 R. Upon depressing the handle s the cross-head P' will be lowered, and vice versa. The upright arm 3 of the rocker R is preferably connected with the corresponding arm of the rocker at the opposite end of the carriage by 20 means of a rod T, which is rendered adjustable in length by a turn-buckle t. This connecting-rod enables the attendant to withdraw one pattern and raise the other simultaneously from either end of the machine.

25 I prefer to provide but one banking-frame U for the two tables, though it is evident that two may be used. To render one frame available for both tables, it is supported on slides V, secured to the inner sides of the standards 30 B and extending parallel with the bed A. The slides consist, preferably, of bars grooved on their inner faces to receive the blocks u , adapted to slide in the grooves. From each block projects a pin on which is fulcrumed a 35 lever U' , one end of which is pivoted to the banking-frame U at about the middle of one side. The other end of the lever carries an adjustable counter-balance u' , the two being 40 preferably united by a bar u^2 . On one side 45 of the banking-frame are provided handles u^3 . The frame itself is merely a rectangular box with no top or bottom, preferably slightly smaller at the bottom, as shown. Pins u^4 project downward from its lower edge to enter 50 holes in the flask and cause the frame to register properly therewith. The construction shown and described permits it to be moved from one side of the compressing apparatus to the other, and to be raised and 55 lowered at will. A lever W is fulcrumed to the frame-work at some convenient place—as, for instance, one of the slides V—and is connected by a rod w with the horizontal arm M^3 on the spindle of the four-way cock M'. A downward movement of the rod causes the 60 carriage to travel to the right, (see Fig. 1,) and vice versa.

To automatically arrest the motion of the carriage at any predetermined point, it is 65 provided with tappets to strike the rock-arm M^2 at the proper instant and close the valve M'. To stop it at either end of its stroke, the rocker-arms 1 may be provided with toes 4, depending into the line of the upright rock-arm M^2 . When the carriage approaches the end 70 of its movement, the toe strikes the rock-arm and turns the cock M' into its intermediate

position, as shown in Fig. 1, cutting off the fluid-pressure from both sides of the piston in the cylinder A', and thereby stopping the carriage and the table N, with its flask, in proper position to be acted on by the compressing apparatus.

Should it be desired to arrest the carriage in the middle of its travel with neither table 75 under the platen, this can be accomplished by means of a tappet X, consisting of a lever pivoted to the side of the carriage at the proper point, and having a toe x adapted to strike the rock-arm M^2 . The tappet is held normally 80 in position to operate by means of a spring x' ; but the workman can prevent it from acting by stepping on the treadle x^2 , and thereby holding the toe x raised until it has passed 85 over the rock-arm M^2 .

The operation of my machine is as follows: The carriage K is placed at the middle of its stroke with neither table under the platen. The two patterns Z—one for the cope and the other for the drag—are firmly secured to the 90 platforms P, one of which is then raised to project the pattern above the table-top N'. One part of the flask—say the cope—is then placed 95 on the table around the pattern and is filled with sand. The banking-frame is then pulled out on the slides V and brought down upon the cope, its pins u^4 entering suitable holes in the upper edge thereof. The frame is filled with sand. The lever W is then moved to open the four-way cock M', whereby the carriage 100 is automatically moved to bring the cope under the platen, the banking-frame moving with it by reason of the blocks u sliding in the ways V. The table stops automatically when it reaches the proper position for the 105 compressing apparatus to operate. The four-way cock H' is then opened to admit fluid-pressure above the piston D, which forces 110 down the yielding platen upon the sand in the banking-frame, pushing it down into the cope, and packing it firmly and with uniform density around the pattern. The plate is then raised and the carriage brought back to the 115 middle position again. The banking-frame is slid to the other end of the ways V and applied to the drag, which has meanwhile been placed upon the other table. The pattern for the cope is then withdrawn and the pattern for the drag elevated by operating one of the levers s. The drag having been filled with 120 sand, the carriage is then shifted to the other end of its stroke to bring the drag under the platen. When the sand has been packed in this part of the flask, the carriage is returned 125 to its central position, and the drag-pattern is withdrawn from its mold by depressing one of the levers s, thereby elevating the cope-pattern again for the formation of a new mold. The connecting-rod T may be omitted and each pattern manipulated independently, if 130 desired. The cope and drag can now be removed to the foundry-floor and united for pouring in the usual manner.

To prevent sand from falling into the car-

riage and bed, they may be floored over below the grooves k^3 a^2 , respectively, suitable slots being left for the arm k' and the lugs n^3 to pass through.

5 Having thus described my invention, what I claim, and desire to secure by Letters Patent, is—

1. In a sand-molding machine, the combination, with the bed A, of the cylinder A', cast integral therewith, a stationary compressing apparatus erected on the bed at or near its middle, a carriage supporting the molds and sliding on the bed, a piston in the cylinder, connected with said carriage, and a four-way valve controlling the flow of fluid-pressure to the cylinder to cause the molds to move under and away from the compressing apparatus at will of the operator, substantially as described.
2. In a sand-molding machine, the combination, with the bed A, having the cylinder A' longitudinally arranged therein, of a stationary compressing apparatus supported by said bed, a carriage for the molds, sliding on the bed, a piston in the cylinder, connected with the carriage, a four-way valve controlling the flow of fluid-pressure to the cylinder, a handle for operating the valve at the will of the operator, and devices moving with the carriage, adapted to operate the valve at predetermined points in the travel of the carriage, substantially as described.
3. In a sand-molding machine, the combination, with the bed A, containing the cylinder A', of the carriage K, sliding on the bed and connected with a piston in the cylinder, the valve M', controlling the admission of fluid-pressure to the cylinder and having its spindle provided with the upright rock-arm M², and tappets attached to the carriage and adapted to strike the arm M², substantially as described.
4. In a sand-molding machine, the combination, with the cylinder containing a piston, of a valve controlling the admission of fluid-pressure to the cylinder and a carriage connected with the piston and carrying the lever X, having the toe x and the spring x' for holding it normally in position to operate the valve, substantially as described.
5. In a sand-molding machine, the combination, with the standards B, of the adjustable cylinder C', the piston D, and piston-rod D', the plate E, sliding on the standards and connected with the piston-rod, the box F, secured to the under side of the plate and having inclined sides, and the flexible bottom F', clamped to the lower edge of the box by the frame f, substantially as described.
6. The combination, with the carriage K, of the table N, comprising two adjustable end portions n n, each having two sides and one end, intermediate removable portions n', and

a removable flat top having an aperture for the passage of the pattern, substantially as 65 described.

7. The combination, with the carriage K, having the grooves k^2 of the tables having end portions n n, provided with flanges n² to slide in the grooves k^2 , and intermediate removable flangeless portions n', substantially as described.

8. The combination, with the carriage K, of the tables for supporting the flasks, consisting of adjustable end portions n n, a set of intermediate removable portions n', and a set of removable tops N', substantially as described.

9. The combination, with the carriage K, of the table N, comprising adjustable end portions n n, each having a depending lug n³, and a shaft O, provided with a right-hand and left-hand screw, one being of greater diameter than the other, said screws engaging with openings in said lugs, substantially as set 85 forth.

10. The combination, with the carriage K, of the cross-head P', having posts p and platform P, the table N, comprising two end portions n n on either side of the posts p, and intermediate portions n', adjacent to said posts, and means for adjusting the end portions, substantially as described.

11. The combination, with the carriage K, of two vertically-movable cross-heads P', two rock-shafts R', carrying rockers R, having arms 1, 2, and 3, two rock-shafts S, with their handles and rock-arms, and an adjustable rod T, connecting the upright rocker-arms 3, substantially as described.

12. In a sand-molding machine, the combination, with the bed and cylinder, of the valve M', whose spindle has an upright arm M², the carriage K, carrying the cross-heads P', and the rockers R for actuating said cross-heads, one arm of each rocker having a toe 4, adapted to strike the arm M² and automatically stop the carriage when it reaches the end of its stroke, substantially as described.

13. In a sand-molding machine, the combination, with the standards B, of the slides V, secured thereto, and a vertically-movable banking-frame U, supported on levers adapted to move along said slides, substantially as described.

14. In a sand-molding machine, the combination, with the standards B, of the horizontal grooved bars V, secured thereto, the blocks u, sliding in the grooves, the counterbalanced levers fulcrumed on said blocks, and the banking-frame U, pivoted to said levers, substantially as described.

THEODOR MISTELSKI.
